BREECH BOLT MECHANISM

Francis I. Rataiczak, Dayton, Ohio, assignor to
General Motors Corporation, Dayton, Ohio, a
corporation of Delaware

Application January 27, 1945, Serial No. 574,844

8 Claims. (Cl. 89—132)

1

This invention relates to ordnance and more particularly to an improved fire control mechanism for use in the .60 caliber machine gun disclosed in my co-pending application S. N. 536,229, filed May 19, 1944, and now designated by the War Department as the Cal. .60 T17E3 Machine Gun.

It is an object of this invention to provide means for synchronizing the firing of the .60 caliber T17E3 machine gun with the operation of an airplane propeller or other moving part.

Another object of this invention is to provide an improved fire control mechanism which may be substituted for the corresponding mechanism on the .60 caliber machine guns of the type now in use.

In the .60 caliber T17E3 machine gun, as disclosed in my co-pending application, the firing pin is carried by the bolt and is moved into firing position by the bolt whenever the bolt moves into its forward position, whereas, in the construction disclosed herein, the firing pin is a spring loaded firing pin controlled by a sear which in turn is controlled by mechanism synchronized with an airplane propeller or the like. It is an object of this invention to mount this sear and the sear trigger within the bolt so as to be movable therewith.

Further objects and advantages of the present invention will be apparent from the following description, reference being had to the accompanying drawings, wherein a preferred form of the present invention is clearly shown.

In the drawings:

Fig. 1 of the drawings shows, somewhat diagrammatically, a machine gun of the type in which my improved fire control mechanism is used;

Fig. 2 is a top view of the bolt head;

Fig. 3 is a side view of the bolt head showing parts broken away;

Fig. 4 is a plan view of the bolt assembly with parts broken away so as to show the fire control mechanism before the bolt head is rotated into its locked position;

Fig. 5 is a vertical sectional view of the bolt assembly showing the elements in the same relative position as in Fig. 4;

Fig. 6 is a sectional view taken substantially on line 6—6 of Fig. 8 showing the relationship of the parts when the bolt and the bolt head are locked in battery and prior to the time that the firing pin is released for movement into firing position;

Fig. 7 is a view similar to Fig. 6 but showing

2

the position of the firing pin after it has moved into firing position and while the bolt is still in battery;

Fig. 8 is a sectional view taken on line 8—8 of Fig. 7; and

Fig. 9 is a sectional view taken in the plane of the sear trigger 92 and is partly diagrammatic, showing the relationship of the synchronizing mechanism to the firing pin sear trigger.

10 Fig. 1 of the drawings diagrammatically shows a gun in which all of the parts except for the bolt assembly and fire control mechanism are identical in construction and operation to the corresponding parts shown in said co-pending application to which reference may be made, if necessary, for a more detailed description of the main gun construction. The most essential parts of the gun are the receiver or breech housing 10, the barrel 20, the breech ring 22, the shell feeding mechanism 24, the bolt buffer 26, the bolt body 30, and the bolt head 32, all of which operate in a manner now well known to those skilled in the art and need no further description except insofar as necessary for an understanding of the operation of the fire control mechanism set forth herein.

The bolt body 30 is mounted in the receiver 10 in accordance with well known practice and is adapted to reciprocate back and forth within the receiver 10 during operation of the gun. As shown in Fig. 4, the bolt body comprises a relatively long, narrow member having a central aperture 80 in which the shank 38 of the bolt head 32 is journaled. The bolt head 32 comprises a rearwardly extending hollow shaft or shank 38 within which a portion of the fire control mechanism is mounted. The forward end of the bolt head is provided with a pair of rollers 42 arranged as shown for cooperation with the cam surfaces 44 provided on the forward end of the bolt body 30 so as to cause relative rotation between the bolt head 32 and the bolt body 30 when the bolt body and bolt head move into battery position. The rollers 42 also cooperate with cam surfaces 56 provided on the breech ring 22 which assist to rotate the bolt head relative to the bolt body 30 and relative to the breech ring 22. This rotation of the bolt head causes it to be held in battery position by means of the complementary interrupted screw type lugs 48 and 50 provided on the bolt head and the breech ring respectively. The interlocking lugs 48 and 50 are of the well known interrupted screw type of lugs. Upon recoil of the barrel 20 together with the breech ring 22, the rollers 42 are moved rearward-

55

ly to engage cam surfaces 54 on the receiver so as to rotate the bolt head relative to the breech ring 22 and the bolt body 30 thereby disengaging the interrupted screw type lugs 48 and 50 so as to allow the bolt head to move back with the bolt body throughout the remainder of the movement of the bolt body. As the cam surfaces 54 rotate the bolt head 32, the rollers 42 also cooperate with the cam surfaces 44 on the bolt body 30 so as to provide relative rotation between the bolt head 32 and the bolt body 30 to cause partial separation of the bolt head 32 and the bolt body 30 through the riding of the lugs 60 in helical slots in the bolt head cam 62.

The shank 38 of the bolt head 32 is provided with oppositely disposed lugs 60 which serve the same purpose as the corresponding lugs in the gun described in said co-pending application. The shank 38 is slidably supported within the bolt head cam 62 which is a sleeve-like member which moves with the bolt body 30 at all times. The lugs 60 engage helical cam slots within the bolt head cam 62 so that relative rotation of the bolt head 32 and the bolt body 30 from the position shown in Figs. 4 and 5 to the position shown in Fig. 6 accompanies the sliding movement of the bolt head 32 toward the bolt body 30. Opposite relative rotation accompanies the sliding movement of the bolt head 32 away from the bolt body. The construction and operation of the lugs 60 and the bolt head cam 62 need no further description as the specific construction of these elements forms no part of this invention. Since the cooperation between the rollers 42 and the cam surfaces 44, 46 and 54 is essentially the same as in the gun set forth in said co-pending application they likewise need no further description.

Referring now to the disclosure in Figs. 4 through 8, the firing pin 64 is slidably mounted within the bolt head as shown. A spring 66 which surrounds the end of the shank 38 acts through the firing pin spring washer 68 and firing pin spring pin 70 to bias the firing pin forward within the bolt head. The firing pin spring pin 70 projects through the slots 72 and 74 (see Figs. 2 and 3) provided in the wall of the bolt head shank 38. The firing pin spring washer 68 is slidably mounted on the exterior of the shank 38 as shown. The rear end of the spring 66 is arranged in engagement with the firing pin spring collar 76 which is threaded onto the shank 38 so as to slide with the shank 38 within the central aperture 80 of the bolt body 30. A notch 82 is provided on the rear end of the firing pin for engagement with the firing pin sear 84. The firing pin sear 84 is pivotally supported on the firing pin sear pivot pin 86 carried by the shank 38. The forward end of the firing pin sear hooks the firing pin 64 at 82 as shown. A compression spring 90 which is held in compression between the collar 76 and the sear 84 normally holds the sear 84 in engagement with the firing pin 64. It should be noted that the bolt body 30 has been shown in a tilted position in Figs. 6, 7 and 8 rather than showing the bolt head and trigger operating mechanism in the tilted position.

A firing pin sear trigger 92 which is pivotally mounted on a pin 94 carried by the main bolt body 30 is arranged for engagement with the rear end of the firing pin sear 84 so as to release the sear from the firing pin by overcoming the force of the spring 90. A spring 96 (see Fig. 8) normally holds the firing pin sear trigger out of firing position. For purposes of illustration, I

have shown the firing pin sear trigger operated by a synchronizing mechanism designated by the reference character 99. The firing pin sear trigger is located so as to be directly in line with the 5 firing pin sear trigger operating member 100 when the bolt body 30 is in its forward or battery position. The member 100 in turn is operated by the reciprocating cam member 102 connected to the 10 cable 104 which in turn is connected to some moving element which operates in synchronism with the propeller. A spring 106 biases the member 100 out of engagement with the firing pin sear trigger 92. The cable 104 is arranged to pass 15 over a pulley 108 which may be secured to the side of the gun by any suitable means (not shown). Since the gun moves longitudinally during recoil, it is essential to arrange the cable and the pulley 108 in the manner shown so that the pull on the cable resulting from the movement 20 of the gun during recoil will not be enough to cause the member 102 to cam the member 100 into gun firing position.

In referring to Figs. 4 through 7 it is apparent 25 that the firing pin sear 84 reciprocates with the bolt head relative to the bolt body during operation of the gun and that it moves in and out of registry with the firing pin sear trigger 92 each time a shell is fired. The rear end of the firing pin sear is therefore provided with an inclined 30 cam surface 112 whereby the extreme rear end of the sear will clear the front face of the trigger 92 regardless of the position of the trigger when the sear moves back relative to the trigger. Referring to Fig. 7 of the drawings, it is apparent that 35 when the bolt head begins separating from the bolt body through the relative rotation between them during recoil, the firing pin spring pin 70 carried by the firing pin 64 contacts the rear end of the bolt head cam 62 whereby the firing pin 64 40 stands still relative to the bolt body and moves with the bolt body rearwardly relative to the bolt head. Thus, when the bolt body moves rearwardly relative to the bolt head, the spring 66 is compressed and the trigger sear 84 moves into 45 engagement with the trigger as shown in Fig. 5. Therefore the spring 66 is compressed between the ring 68 and the collar 76. The ring 68 moves rearwardly with the bolt body 30 relative to the collar 76 which is fastened to the rear end of the shank 50 32. The firing pin 64 moves rearwardly with the ring 68. The bolt head 32 lags behind the bolt body 30 during the recoil producing the relative movement between the bolt body and the bolt head which performs the withdrawal of the firing pin and the compression of the spring 66. Upon 55 locking the breech bolt to the barrel upon the return of the bolt to battery position, the bolt head together with all of the parts carried thereby move from the relative position in which they are shown in Fig. 5 to the relative position in which they are shown in Fig. 6 in which relative position the firing pin spring is compressed and the sear is in registry with the trigger 92. Thus, with the parts 60 arranged as shown in Fig. 6 (and these parts are arranged in this manner only when the bolt body is in its forward position and the gun is ready to be fired) operation of the trigger 92 by the synchronizing mechanism 99 releases the firing pin 65 from the sear.

70 While the form of embodiment of the invention as herein disclosed constitutes a preferred form, it is to be understood that other forms might be adopted, as may come within the scope of the 75 claims which follow.

What is claimed is as follows:

1. In a rapid fire machine gun having a reciprocating bolt body and a bolt head carried by the bolt body and rotatable relative to the bolt body, a firing pin means movably carried within said bolt head for movement into and out of firing position, means preventing relative rotation between said firing pin means and said bolt head, a spring urging said firing pin means to move forward into firing position, a sear carried by said bolt head for releasably holding said pin means out of firing position to prevent its forward movement under the impetus of said spring, and trigger means carried by said bolt body for operating said sear to release said pin means for movement to firing position by said spring.

2. In a rapid fire machine gun having a reciprocating bolt body and a bolt head carried by the bolt body and rotatable relative to the bolt body, a firing pin means movably carried within said bolt head for movement into and out of firing position, a spring urging said firing pin means to move forward into firing position, a sear for releasably holding said pin means out of firing position to prevent its forward movement under the impetus of said spring, and trigger means carried by said bolt body for operating said sear to release said pin means for movement to firing position by said spring.

3. In a rapid fire machine gun having a reciprocating bolt body and a bolt head carried by the bolt body and rotatable relative to the bolt body, a firing pin means movably carried within said bolt head for movement into and out of firing position, a spring urging said firing pin means to move forward into firing position, a sear for releasably holding said pin means out of firing position to prevent its forward movement under the impetus of said spring, and trigger means carried by said bolt body for operating said sear to release said pin means for movement to firing position by said spring, a pivot for said sear carried by said bolt head whereby said sear is pivotally secured to said bolt head so as to move with said bolt head relative to said bolt body.

4. In a rapid fire machine gun having a breech housing, a reciprocating bolt body within said breech housing, and a bolt head carried by said bolt body and rotatable relative to the bolt body, a firing pin means movably carried within said bolt head for movement into and out of firing position, a sear carried by said bolt head for releasably holding said pin means out of firing position to prevent its forward movement under the impetus of said spring, sear operating means carried by said bolt body for moving said sear to release said pin means for movement to firing position by said spring, and means carried by said breech housing for engaging said sear operating means.

5. Fire control mechanism for use in a rapid fire machine gun comprising in combination, a reciprocating bolt body, a bolt head rotatably carried by the bolt body, a firing pin slidably disposed within said bolt head, a sear pivotally secured

within said bolt head for engaging said firing pin, and trigger means carried by said bolt body for engaging the sear.

6. In a rapid fire machine gun, a bolt body having a central aperture, a bolt head, said bolt head having a rearwardly extending hollow shaft journaled in said aperture for reciprocation and rotation relative to said bolt body, a firing pin slidably supported within said bolt head, a sear for releasably holding said firing pin out of firing position, means for supporting said sear within said hollow shaft, means carried by said bolt body for operating said sear, and means for biasing said firing pin into firing position including spring means within said aperture and surrounding said hollow shaft.

7. In a rapid fire machine gun, a bolt body having a bearing aperture, a bolt head, said bolt head having a rearwardly extending hollow shaft journaled in said bearing aperture, a firing pin slidably mounted within said hollow shaft, a compression spring disposed within said bearing aperture and surrounding said hollow shaft, means connecting said spring and said firing pin so as to bias said firing pin forwardly into firing position, and sear means disposed within said hollow shaft for releasably holding said firing pin out of firing position.

8. In a rapid fire machine gun, the combination, a breech housing, a reciprocating bolt body disposed within said housing, a bolt head rotatably mounted for reciprocation relative to the bolt body, a firing pin slidably mounted within said bolt head, a spring urging said firing pin towards firing position, a sear for holding said pin out of firing position, sear operating trigger means carried by said bolt body, means carried by said breech housing for actuating said trigger means, said last named means comprising a first reciprocating member for engaging said sear operating means and a second reciprocating member arranged at right angles to said first reciprocating member and having a cam surface for actuating said first reciprocating member, cable means having one end secured to said second reciprocating member, and pulley means for said cable carried by said breech housing, said cable means having said one end arranged parallel to said housing and having an operating portion passing over said pulley and extending substantially at right angles to said housing.

FRANCIS I. RATAICZAK.
